CLAIM

The ornamental design for a measuring apparatus for an ultrasonic diagnosis apparatus, as shown and described.

DESCRIPTION

FIG. 1 is a front, top and right side perspective view of a measuring apparatus for an ultrasonic diagnosis apparatus, showing our new design;

FIG. 2 is a rear, top and left side perspective view thereof with a door opened and with a disk tray drawn out;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.
